REFRIGERATOR DRAIN

Charles F. Belshaw, Greenville, Mich.

Application January 24, 1936, Serial No. 60,631

5 Claims. (Cl. 137—21)

This invention relates to refrigerator drains and more particularly to that funnel shaped device and the conduit leading therefrom through the floor beneath an ice refrigerator and into 5 which the water from the melting ice in the refrigerator drips and is carried away and the general object of the invention is to prevent moisture due to condensation on the outside of the funnel flowing downwardly onto the floor.

10 Another object of the invention is to provide means for entrapping sediment from the ice water to prevent it flowing into the drain pipe and also to provide means for chemically treating the drain water to destroy the algae or fungi therein, these 15 tending to clog the drain pipe.

Of course, in using ice refrigerators, it is necessary to dispose of the water from the ice melted in the refrigerator which water conventionally is deposited through a drip pipe at the bottom of 20 the refrigerator and it has become customary to extend a drain pipe from the refrigeration location to a place of disposal of said water and to provide the drain pipe with a funnel shaped element into which the water from the refrigerator drip pipe is received.

25 The drain pipe customarily extends through the floor beneath the refrigerator and the water dripping from the refrigerator is very cold, being only slightly above freezing temperature, which water 30 cools the funnel and drain pipe, thus causing condensation from the surrounding air to accumulate on the exterior of the funnel and drain pipe above the floor and to run downward and be deposited upon the floor which has been a very 35 objectionable condition.

The drain pipe, used to carry away the water from the melted ice, frequently clogs by collection of foreign substances therein. Such foreign 40 substances may be solid matter of different kinds frozen in the ice or algae or fungi, a vegetable organism which finds its way into the drain water from one source or another and is deposited in the drain pipe where it grows to sufficient proportions to clog the pipe. This invention provides 45 means for preventing clogging of drain pipes by an especially devised trap to catch the heavy foreign substances to prevent their passing into the drain pipe and also means for chemically treating the drain water to destroy the vegetable fungi before it passes into the drain pipe.

An object of this invention is to eliminate the 50 deposit and collection of this water of condensation upon the floor beneath the refrigerator which 55 is accomplished partly by insulating a portion of the drain structure so that it will not be cooled on its exterior surface to cause condensation to occur and partly by providing means for carrying such condensation as does occur into the conduit 60 which passes through the floor so that it will

not be deposited upon the upper surface of the floor.

The invention provides various novel features of construction and arrangement as hereinafter more fully described and particularly pointed out 5 in the claims, reference being had to the accompanying drawing, in which,

Fig. 1 is a fragmentary sectional elevation of a floor structure and the lower part of a refrigerator with a drain embodying this invention applied thereto.

Fig. 2 is a vertical sectional elevation of one form of structure embodying the invention.

Fig. 3 is an enlarged elevation of one of the elements of this structure removed from the assembly.

Figs. 4, 5 and 6 are respectively enlarged sectional plans on the lines 4—4, 5—5 and 6—6 of Fig. 2.

Fig. 7 is a vertical sectional elevation of a second form of structure embodying the invention.

Fig. 8 is an enlarged sectional plan on the line 8—8 of Fig. 7.

Fig. 9 is a sectional elevation of a third form of structure embodying the invention, and

Figs. 10, and 11, are respectively enlarged sectional plans on the lines 10—10 and 11—11 of Fig. 9.

Like numbers refer to like parts in all the figures of the drawing.

The refrigerator 1 stands on the floor 2 and is 30 provided with the conventional drip pipe 3 through which water from the melted ice in the interior of the refrigerator passes. A drain pipe 4 extends from below the refrigerator through the floor 2 and thence to a place of disposal of the water which may be near by or at a considerable distance the length of said drain pipe having no material bearing upon the present invention.

40 The form of structure shown in Figs. 2, 3, 4, 5 and 6 embodying this invention comprises a funnel 5 supported upon and communicating with a neck 6 which extends upwardly from a member 7 which forms a part of the water conduit. An annular trough 8 surrounds the base of the neck 6 and constitutes a part of the member 7 and the trough 8 has openings 9 through it communicating with the interior of the member 7 whereby water collecting in the trough will drain into the 50 interior of the member 7.

Below the member 7 is a tubular connector 10 having its upper end outwardly flanged and communicating with an opening in the bottom of the member 7. A cup shaped coupling member 12 55 having an opening in its bottom surrounds the member 7 and the connector 10 projects through the opening, the exterior of the member 7 and the interior of the coupling 12 being correspondingly threaded and screwed together to form a 60

connection between the members 7 and 10. The threads of the coupling 12 are the same as those of a standard garden hose coupling so that the members 7 with the funnel 5 attached may be unscrewed from the coupling 12 and a hose attached in their place for the purpose hereafter described.

Rubber insulating sleeves 13 and 14 surround the coupling 12 and the connector 10 and extend below it to also surround the upper end of the drain pipe 4 projecting above the floor. The inner rubber sleeve 13 is in the nature of a substantially straight rubber hose which preferably has longitudinal corrugations on its outer surface and the connector 10 is thrust into the upper end of the inner sleeve 13 preferably being provided with annular beads 10a to frictionally retain it in place in the tube. It is to be noted that insulating material other than rubber can be used for the tube 13.

The outer tube 14 surrounds the tube 13 and extends upwardly and is expanded to also surround the coupling 12 and its upper end is folded backwardly and extends downwardly over the outer sleeve to provide a reinforcement of the upper end of the structure and also to increase its tension and frictional grip upon the inner parts. A clamp 15 preferably surrounds the outer sleeve near its lower end and is used to clamp the sleeve structure upon the drain pipe 4.

The corrugations in the outer surface of the inner sleeve 13 provide a plurality of air spaces which increase the heat insulating effect of the structure, these spaces being closed by compression of the rubber both near the upper end of the sleeve where it is surrounded by the double tension caused by the doubling of the sleeve, and also at the point where the clamp 15 is applied, thus confining the air in the spaces between the corrugations.

A combined sediment trap and chemical holder may be utilized in this device consisting of a funnel shaped member 16 removably supported within the funnel 5 and having an upwardly extending tube 17 communicating with its opening and also with the neck 6 of the funnel 5. The funnel 16 of this trap fits sufficiently closely into the funnel 5 to cause water traveling down the funnel wall to flow into the trap and also any sediment carried by the water will move into the trap and be deposited therein, the water rising in the trap until it flows over the top of the tube 17. This trap may also be used to contain a solid chemical for the purpose hereafter described.

The form of structure shown in Figs. 7 and 8 comprises the tube 20 which extends through the floor and has its lower end joined in a suitable manner with the drain pipe 4. The upper end 60 of the tube 20 is enlarged in diameter at 21 and a funnel 22 has a vertically fluted or corrugated neck 23 which extends through the enlarged upper portion 21 of the tube 20 and fits into the lower portion of the tube which structure provides an annular trough 24 surrounding the neck 23 of the funnel at the upper end of the tube 20 and the flutes or corrugations in the neck provide passages through which water collecting in the trough may drain into the interior of the tube. 70 If desired the tube 20 may have a double enlargement at its upper end, the first enlargement being the same diameter as the exterior diameter of the neck 23, the tube diameter itself being smaller than the neck, which forms a suitable rigid support for the neck. The neck 23 of

the funnel extends upwardly within the funnel at 23a providing a trap and chemical holder for the purposes hereafter described.

That portion of the tube 20 extending above the floor is surrounded by heat insulating sleeve 25, preferably of rubber, which sleeve may be formed of a piece of tubing of uniform diameter which, when thrust over the tube will stretch to accommodate itself to the enlarged diameter of the upper end of the tube. If desired other insulation material may be applied in suitable manner as by moulding.

The form of structure shown in Figs. 9, 10 and 11 has a funnel 30 with a long neck 31 provided at its lower end with a conventional pipe connection 32 by means of which it is connected to the drain pipe 4. The neck 31 of the funnel is surrounded by a metal tubular sleeve 33, larger in diameter than the neck 31, both the sleeve 33 and the neck 31 extending through the floor and the sleeve 33 is provided with a flange 34 which rests upon the floor.

The upper end of the sleeve 33 is flared outwardly at 35 and an insulating spacer 36 surrounds the funnel neck 31 and is located in and engages the flared portion 35 of the sleeve 33 which centers the upper end of the neck in the sleeve maintaining a space between the neck and the sleeve. The spacer 36 has notches 37 which permit condensation flowing down the outer surface of the funnel and the neck to pass through the spacer 36 and continue downwardly inside of the sleeve, this water tending to adhere to the outer surface of the neck in its downward flow because of surface attraction.

Operation

The form of device of Fig. 2 is most desirably used in cases where the drain pipe 4 is inaccessible below the floor. By modern methods of piping houses the drain pipe 4 may be of flexible copper tubing and may be run through partitions of a house and through the floor and in such an installation the only portion of the drain pipe which is accessible is that part which projects above the floor. In the device of Fig. 2 the structure is adapted to be applied to the end of the drain pipe 4 projecting above the floor without requiring access to the drain pipe below the floor.

In the form of Fig. 2 when used without the sediment trap the cold water from the refrigerator will drip into the funnel 5 and considerably cool it and moisture will collect on its outer surface from the surrounding atmosphere which moisture will flow downwardly by gravity and find its way into the annular trough 8 from where it will pass through the openings 9 into the interior of the member 7 and eventually flow through the drain pipe 4 together with the water from the melted ice. The insulation consisting of the sleeves 13 and 14 surrounding the lower part of the structure above the floor will prevent the outer surface exposed to the air becoming cold and therefore condensation will not occur. By this means condensation occurring on the funnel will drain into the drain pipe 4 and be carried away while no condensation can occur on the lower part of the structure and therefore no water of condensation will find its way to the floor.

When the sediment trap is used in this type of structure the water dripping from the pipe 3 may either fall onto the surface of the funnel 5 or into the funnel 16 but in either case the water

with any foreign matter it contains will find its way into the funnel 16 which will fill up to the level of the top of the tube 17 where it will drain from the tube and be deposited in the predescribed passages. Any sediment heavier than water will collect at the base of the funnel 16 and will be prevented from flowing through the drain pipe and this sediment trap comprising the funnel 16 and the tube 17 may be easily bodily lifted from the funnel 5 to clean the sediment from it.

This device may also be conveniently used as a means for chemically treating the drain water to destroy the fungi in it. A suitable chemical in solid form may be placed in the base of the funnel 16 where it will be slowly dissolved into the drain water, this chemical being of a nature to destroy the vegetable organisms in the water which would tend to deposit and grow in the drain pipe to clog it.

In spite of the precaution of trapping the sediment and destroying the fungi in the water it is likely that the drain pipe may become clogged and in this structure the member 7 including the members above supported by it may be unscrewed from the coupling member 12 and a hose connected to the coupling member and communicated with a source of water under pressure which can be led into the drain pipe with sufficient force to dislodge and wash out whatever sediment may have collected therein.

The structure of Fig. 7 is similar in general operation to that in Fig. 2, the water being deposited in the funnel 22 will collect at the base of the funnel and rise to the level of the top of the upward projection 23a of the neck where it will flow downward through the neck and the heavy sediment will precipitate and remain in the bottom of the funnel. A solid chemical may be used in the funnel to treat the water to destroy the vegetable fungi.

The condensation occurring on the outside of the funnel 22 flows downward following the neck 23 into the trough 24 and thence through the corrugations into the interior of the tube 20 and the insulating sleeve 25 surrounding the tube 20 prevents condensation on its outer surface. In this structure the funnel 22 and its neck 23 may be readily removed from the tube 20 to clean the sediment from it.

In the structure of Fig. 9 condensation on the outside of funnel 30 will flow downwardly through the notches 37 in the spacer 36 and through the space within the sleeve 33 surrounding the exterior of the neck 31 and will be carried below the floor where it will either be carried away by flowing along the exterior of the drain pipe 4 or will evaporate. Although the condensation occurring on the exterior of the funnel in this structure is not carried into the interior of the drain pipe it is carried positively through the floor within the sleeve 33 and is prevented thereby from depositing upon the floor.

The sleeve 33 surrounding the neck 31 with an air space between them serves as an insulator to prevent transfer of heat between the sleeve and the neck 31 thus preventing the sleeve from becoming cold enough to cause condensation to occur on its exterior exposed surface and the spacer 36 is of heat insulating material such as rubber which prevents conductivity through it between the sleeve and the neck.

The invention is defined in the appended claims and is to be considered comprehensive of all forms of structure coming within their scope.

I claim:

1. A drain construction adapted to be associated with a refrigerator having an outlet leading therefrom, the combination of, a hollow member of relatively large cross section at its top portion and relatively small cross section at its lower portion, said member being open at both of its ends, said upper open end adapted to receive water and sediment from a refrigerator, a tubular member tightly joined at its exterior surface to the periphery of the lower opening, said tubular member extending upwardly into the first mentioned member to a medial point thereof and also extending downwardly therefrom, encircling means located about the said downwardly extending portion, a part of said encircling means being spaced from the tubular member whereby a trough is formed around the said tubular member, said aforesaid structure having one or more openings leading from the bottom of the trough into the interior of the said tubular member for the purpose described.

2. A device of the class described comprising a drain pipe, a connector communicating with said drain pipe, an insulating sleeve surrounding a part of said connector and a part of said drain pipe and connecting them together, a funnel above and communicating with the upper end of said connector and means for conducting water condensing on the exterior of said funnel into the interior of said connector.

3. A device of the class described comprising the elements defined in claim 2, said means including an annular trough near the upper end of said connector, said trough having openings communicating with the interior of said connector.

4. In a drain construction adapted to be associated with a refrigerator having an outlet leading therefrom, the combination of a funnel located below the outlet and having its exterior surface exposed to the surrounding atmosphere, a connector extending downwardly from said funnel, an insulating member surrounding said connector, and means for conducting water condensing on the exterior of said funnel into said connector.

5. In a drain construction adapted to be associated with a refrigerator having an outlet leading therefrom, the combination of a funnel-shaped member having its larger end uppermost to receive water and sediment from a refrigerator, a member of substantially tubular shape connected to the smaller end of said funnel-shaped member by a water tight joint and extending upwardly within the same but terminating below the top edge thereof for the purpose described, a second member of tubular shape and of a diameter greater than that of said first tubular-shaped member connected to the lower end of said first tubular-shaped member and having an outwardly projecting annular trough portion, said trough portion having an opening leading downwardly into the interior of said second tubular-shaped member to conduct condensate formed on the exterior of the funnel-shaped member into said second tubular-shaped member.

CHARLES F. BELSHAW.
